Specification for Design.

Patented Dec. 9, 1919.

Application filed August 7, 1919. Serial No. 315,993. Term of patent 7 years.

To all whom it may concern:

Be it known that I, JOHN H. WILSON, a citizen of the United States, residing at Minneapolis, in the county of Hennepin and State of Minnesota, have invented a new, original, and ornamental Design for a Clock-Stand, of which the following is a specification.

Referring to the drawing:—

The figure of the drawing is a perspective view of a clock stand, showing my new design.

I claim:—

The new, original and ornamental design for a clock stand, substantially as shown.

In testimony, that I claim the foregoing as my own, I have hereto affixed my signature in the presence of two witnesses.

JOHN H. WILSON.
